UNITED STATES PATENT OFFICE

2,149,626

STEAM DRIER FOR USE ON LOCOMOTIVES

Pasquale Pascale, New York, N. Y., assignor to
Dri-Steam Valve Corporation, New York, N. Y.,
a corporation of Delaware

Application September 18, 1934, Serial No. 744,518
Renewed October 12, 1936

6 Claims. (Cl. 183—112)

This invention relates to a device for removing particles of entrained moisture and other foreign matter from gases, and in particular to a device adapted for use as a steam drier on locomotives.

5 I have devised and patented a number of throttle and other valves having as a part thereof drying devices designed to dry steam before passing it to the point of work.

These, in practice, have been exceptionally 10 efficient and the improvements about to be described are improvements that have been conceived as a result of my long experience and many experiments in the art, and my object now is to improve on my former constructions. I now 15 present a steam drier that more efficiently and completely dries the steam than any of which I am aware, due in this instance to the manner in which the steam is introduced into the drier, and the construction of the steam drying surfaces 20 and the increase in the area of the interior parts against which the steam impinges, whereby its direction of travel is changed several times before it passes through the superheater or directed to the cylinders, as the case may be, the main object being to improve the steam by denuding it 25 of a maximum amount of moisture.

Another and further object, and which from a practical standpoint is important, is to so construct the parts especially the steam drying 30 parts, that they can be readily manufactured at a most much less than my former constructions. This is accomplished by making the drier in the main of separate plates, each provided with numerous nozzles, which plates with their nozzles, 35 may be cast instead of heretofore having to drill the nozzles through the surface of the cylindrical drier element, the plates in the present instance being separately attached to suitable supports and when assembled will form a dry steam chamber 40 communicating with a dry pipe or other outlet leading to the point of work, whether to and through a superheater or not.

Heretofore, as intimated, the main drying element of my inventions has been a cylindrical shell, the surface of which has been provided, by 45 drilling, with numerous small openings or nozzles, but experiment and experience have shown the form disclosed in the drawings to be more efficient. In this form the element is made up 50 of a number of plates arranged about a common axis to form a many sided body, hexagonal in the present instance, thereby presenting a much greater surface to the steam, and at the same time directing its flow toward the center of the 55 assembly and obliquely against the faces of the

plates, thus preventing the moisture or separate which has been taken from the steam, from passing through the nozzles and facilitates its passing to the drain pipes leading back into the boiler.

5 A further object is to so form the cage or outer casing or "turbine" of the drier, that the steam passing therethrough will be directed downwardly against the plates of the drier proper, thus causing the separate or water to drop to the bottom of the drainage space or the chamber provided therefor and avoid the possibility of its being picked up and carried by the steam through 10 the nozzles.

In the drawings:

Figure 1 is an elevation of the drier;

Figure 2 is an enlarged elevation and partial section, a part of the cage being broken away showing the arrangement of the drier plate and supporting parts;

Figure 3 is a detail fragmentary perspective 20 view showing a portion of the upper edge of the member that carries the posts to which the drier plates are connected;

Figure 4 is a top plan view partly broken away 25 showing a portion of the plates and a portion of their supports;

Figure 5 is a section taken about on line 5—5 of Figure 4;

Figure 6 is an enlarged section of one of the 30 nozzles.

Referring to the drawings, the numeral 1 designates the outlet or dry pipe leading to the superheater or to the engine, as the case may be. This is formed with a flange 2 which is bolted to the annular flange 3 of the plate supporting ring 4. 35 This ring is formed with an outwardly flaring flange 5 at its upper edge, which is angular in shape, or rather it is formed with a number, six in the present instance, of straight sides. Each side is provided with a ledge or seat 6 to 40 receive the lower edges of the drier plates 7.

At the points of intersection or corners of the flange 5, I provide at each a vertical post 8. The upper ends of these posts are connected by bars 9, the posts and bars constituting a frame to 45 which the drier plates are connected. Each post, at its bottom and top, is provided with a boss or reinforcement 10, and about midway of these posts there is another boss 11 provided, and all of the bosses have threaded sockets to receive 50 short bolts 12 and 13 by which the plates are secured to the posts and frame in steam tight fashion. The plates are provided with numerous small generally conically shaped nozzles 13' having reduced inlet ends protruding outwardly 55

from the plate to present a comb or brush-like surface against which the incoming steam is directed. These nozzles, as shown in Figure 6, increase in cross-section from the inlet openings 5 14 to the exit openings 15.

The numeral 16 designates the cage or turbine. This is secured to the lower edge of the plate supporting ring 4 by short bolts 17 and entirely surrounds the drier proper and is covered by a 10 head or plate 18 secured to the upper edge of the cage by bolts 19. The cover 18 is also the cover for the central drier assembly, as shown best in Fig. 5, and with the member 4 and the plates 7 forms a large dry-steam chamber 20 open at its 15 lower end and through the hollow member 4, communicates with the outlet pipe 1. The cover 18 is depressed centrally and provided with a threaded aperture for the reception of an eye bolt 21 by which the whole structure, which is 20 quite heavy, can be conveniently handled.

The upper part of the wall of the cage is provided at intervals, circumferentially, with narrow vanes 22, spaced apart to form narrow slits or long narrow openings 23. The vanes are acute 25 in cross section, as shown best in Figs. 2 and 5, with their entrances pointing downwardly toward the outside of the cage, while their outlets point downwardly toward the drier plates so that the steam is directed downwardly against said 30 plates, thus aiding the dropping of the water or separate to the bottom of the drain chamber 24, which is between the inner wall of the cage and the member 4, and at the lower portion of the drier. At intervals the flange 3 is cut out to form 35 drainage openings 25, through which and also through the flange of the pipe 1, drainage pipes 26 are let in, and through which pipes the separate rate flows back into the boiler. Each drainage pipe is provided with a check valve which is 40 automatically opened when a column of water forms therein to drain the water back into the boiler.

In operation, the drier being located in the steam space of the boiler, steam passes between 45 the vanes, taking out part of its moisture, and downwardly from all sides of the drier simultaneously toward the center thereof and against the drier plates and the surfaces of the nozzles, which as before stated, and by reason of the 50 tremendously increased surfaces and the shape of the nozzles, the steam is denuded of a maximum amount of water and is delivered in a substantially dry state through the nozzles and into the chamber 20, from whence it passes to and 55 through the dry pipe to the superheater, directly to the cylinders of the engine, or elsewhere where it is to be utilized.

I have illustrated the drier plates as being flat and the drier proper made up of a series 60 of such plates, but it will be understood that the drier may be made up of a number of curved sections or sections of other surface increasing character and secured to the frame in any suitable manner.

65 It will be observed that by reason of the arcuate shape of the inlet openings and their location in the wall of the casing with relation to the nozzles on the drier plate, that the steam will be caused to impinge with great force and 70 at high velocity against the cone shaped surfaces of the nozzles with a tendency to force the separate toward the bottom of the chamber 24, from whence it will pass through the pipes 26 and check valve, back into the boiler. This downward 75 direction of the projection of the steam

against the numerous nozzles, facilitates in removing the moisture and particles of other entrained matter since the steam is forced, due to the structural arrangement of my drier, to undergo considerable turbulence before it is finally combed through the protruding inlet ends of nozzles 13'. While the form of my invention herein disclosed is described in connection with the drying of steam, it will be readily apparent that my invention may also be used for drying 10 and cleaning other gases as well. It will therefore be understood that wherever the term "steam" has been used in the specification and appended claims that it is to be regarded in a generic sense as including other gases. 15

Having thus described my invention, what I claim is:

1. A steam drier including an inlet opening and an outlet opening, a plurality of plates interposed between said openings, and forming an outer and an inner chamber in said casing, the inner chamber communicating with the outlet opening, the plates being provided with numerous protruding nozzles establishing communication between the outer and inner chambers, the nozzles having small entrance openings and comparatively large outlet openings. 20

2. A steam drier including a casing provided with numerous circumferentially arranged vanes in the upper portion thereof, arcuate in cross section, thereby forming a plurality of ports or slits, also arcuate in shape, and adapted to direct the steam as it enters the casing in a downward direction, an outlet opening for the casing, a plurality of plates interposed between the inlet opening and the outlet opening, said plates being provided with a plurality of nozzles with their ends protruding from the plates and extending toward the inlet opening, so that steam entering the casing will be projected downwardly 40 against said nozzles. 35

3. A steam drier including a casing having inlet openings and an outlet opening, a plurality of plates supported in said casing and forming a barrier for the steam as it passes to the outlet, 45 said plates being provided with a plurality of nozzles extending toward the inlet openings and protruding from the faces of the plates, said nozzles being formed with contracted inlet openings, the inlet openings of the casing being so shaped 50 and arranged as to project the steam that enters the inlet openings of the casing downwardly against the nozzles.

4. A steam drier including a casing having numerous inlet openings in the upper part thereof, and an outlet opening, a plate supporting ring supported in said casing, a plurality of plates supported by said ring and forming a chamber within said plates communicating with the outlet opening, said plates being provided 60 with numerous nozzles protruding from the faces of the plates toward the steam inlet openings, and through which the steam must pass before passing to the outlet opening, said nozzles being in the shape of truncated cones tapering toward 65 their steam inlet ends, and having the orifices therein enlarging outwardly toward the steam outlet side. 55

5. A steam drier including a casing having inlet openings therein and an outlet opening, 70 a steam drier means within the casing comprising a hollow body provided with numerous nozzles protruding from the outer wall thereof and serving as means of communication between the casing and the outlet opening of the drier, 75

and also to increase the impinging surface of the incoming steam and to break up the currents thereof before passing through the nozzles whereby to promote separation of moisture from the steam, and said nozzles further defining tapered passages through said wall increasing in diameter in the direction of the steam flow.

5. In a steam drier, in combination, a casing having inlet openings and an outlet opening, a steam drying element interposed between said inlet and outlet openings so that incoming steam must pass there through before reaching the outlet opening, said element comprising a vertically extending wall carrying a multitude of

nozzles which project outwardly from the surface thereof on the steam receiving side and presenting extended raised surfaces for contact with the incoming steam and said nozzles further defining tapered steam passages through said wall 5 increasing in diameter in the direction of the steam flow, said inlet openings being so disposed with respect to said drying element as to deflect the entering steam obliquely toward said wall across and about said nozzles, and means 10 guiding separate out of the path of flow of the steam and withdrawing it from the casing through an opening in advance of said wall.

PASQUALE PASCALE.

CERTIFICATE OF CORRECTION.

Patent No. 2,149,626.

March 7, 1939.

PASQUALE PASCALE.

It is hereby certified that error appears in the printed specification of the above numbered patent requiring correction as follows: Page 1, first column, line 31, for the word "most" read cost; page 2, first column, line 24, for "actuate" read arcuate; and that the said Letters Patent should be read with this correction therein that the same may conform to the record of the case in the Patent Office.

Signed and sealed this 22nd day of August, A. D. 1939.

Leslie Frazer
